UNITED STATES PATENT OFFICE

EARL V. VARCOE, OF PHILADELPHIA, PENNSYLVANIA

BOILER

Application filed May 24, 1927. Serial No. 193,786.

My invention relates to water tube boilers especially designed for use in self-propelled vehicles, such as automobiles, and has for an object to provide a boiler capable of generating a larger quantity of steam relatively to its size than is possible with boilers now in use.

It is a well known fact that the boiler tubes disposed in close proximity to the fire deteriorates more rapidly than do those farther away and that the boiler parts containing the division between steam and water are more subject to the chemical action of the water than are the other boiler parts.

15 A form of apparatus by which the above objects are accomplished is provided in the nature of a plurality of coiled tubes extending between headers, said tubes lying substantially concentrically within the same

20 plane. The efficiency of this construction may be increased by providing a plurality of coils arranged in the above manner and by filling the space at the center of these coils with tubes projecting transversely of the opening at an inclination to the axis thereof, and having their ends in communication with the said head.

Associated with these coils may be provided an insulating casing and a suitable heating unit.

Figure 1 is a side elevation of a boiler embodying my invention but showing the casing in cross section and having the asbestos omitted from between the headers on one side.

Figure 2 is a fragmentary perspective view of one of the headers shown in Figure 1, and

Figure 3 a sectional view taken on line 3—3 on Figure 1.

40 Figure 4 is a top plan view of one of the steam generating units shown in Figure 1 and also shows the boiler casing in cross section.

Figure 5 is a central cross sectional view taken on line 5—5 on Figure 4, showing the steam generator unit only.

Referring now more in detail to the drawings, the boiler consists primarily of a plurality of steam generating units 10, a steam unit 11 and a burner 12; all of which are en-

closed in a suitable boiler casing 13. Each steam generating unit 10 has been shown as consisting of a header 14, a header 14^a, a plurality of pairs of coiled tubes 15, 16, 17 and 18, extending from one header to the other, and a plurality of bent tubes 19 extending from one header to the other. The upper coiled tubes have been designated by the numerals 15, 16, 17 and 18 while the exponent "a" has been added to these numerals for designating the lower coiled tubes.

Tubes 15 and 15^a extend from header 14, make approximately one and one-half turns and enter header 14^a; tubes 16 and 16^a extend from header 14 to header 14^a making approximately one and one-half turns inside of and concentric with the coil made by tubes 15 and 15^a; tubes 17 and 17^a extend from header 14 to header 14^a making approximately one and one-half turns inside of and concentric with the coil made by tubes 16 and 16^a; and tubes 18 and 18^a extend from header 14 to header 14^a making approximately one and one-half turns inside of and concentric with the coil made by tubes 17 and 17^a. In order to fill up the space inside of the coil made by tubes 18, tubes 19 extend horizontally from header 14, at a point below the coiled tubes, then forwardly and upwardly through this coil, and into header 14^a.

While but four pairs of coiled tubes have been shown, in practice I employ nine pairs of coiled tubes in the size of header shown in Figure 4, so that they are disposed in close proximity to one another and substantially fill the space from the coil formed by tubes 18 to the inside of the boiler casing. While I have shown but three tubes 19, in practice I employ eight of these tubes in the size header shown in order to completely fill the space inside the coil made by tubes 18. The tubes 19 nearest the sides of headers 14 and 14^a extend farther toward the center of the boiler and are bent more directly upward while the other tubes 19 are bent as shown in Figures 1 and 5. In this manner, the interior of boiler casing 13 is practically filled with tubes disposed in close proximity to one another so as to extract the maximum amount of heat from the products of combustion delivered

by burner 12. Further, more than two tubes may be employed in each coil when so desired in order to increase the heating surface of the boiler.

5 Tubes 15 to 19 inclusive extend through one side wall of header 14 and are suitably welded or brazed on the inside of the header so that there is no weld or other joint exposed to the action of the flame from burner 12. 10 The other side of header 14 consists of a removable cover plate 20 secured in place by suitable bolts 21 and the header is prevented from leaking at this point by a gasket 22 interposed between the cover plate and the 15 body of the header. Header 14^a is the same as header 14 but is positioned bottom upwards in the boiler, relatively to header 14. Both the upper and lower sides of the headers merge into pipe bosses 23 by means of which 20 two headers may be clamped together; it being understood that a suitable gasket is placed between the abutting bosses.

Steam unit 11 has been shown as having a steam tube 24, extending from a steam header 25, making approximately a turn and a half and entering a header 25^a, and steam tubes 26 and 27, extending from header 25, making approximately one and one-half turns concentric with the coil made by tube 24 and 30 with each other and entering header 25^a. The steam tubes are much larger than the steam generating tubes and are welded to the inside of the headers so that the welds are not exposed to the action of the hot gases.

35 These tubes act as a reservoir for the steam generated and a steam outlet 28 is connected to one of the steam tubes in close proximity to header 25^a so that steam may be drawn from all three in practically equal quantities.

40 Steam headers 25 and 25^a are alike and are similar to headers 14 with the exception that they are not provided with pipe bosses and are provided with but three connections for steam tubes. The bottom of each header is 45 provided with two openings, adapted to register with pipe bosses 23 on headers 14, and with two smaller apertures in its top in line with these openings in order to accommodate two rods 29 which are adapted to bolt the several sections together. The outside of header 50 25 is closed with a cover plate in a manner similar to header 14.

55 In assembling the boiler, a steam generating unit 10 is aligned with a steam unit 11 and as many more steam generating units 10 aligned with the first one as are required to produce a boiler of the desired capacity. A casting 30 is then placed against the lowermost header 14^a and a pair of rods 29 inserted through the line of headers and drawn tight to hold the units in fixed relation with one another; it being understood that suitable gaskets are placed between pipe bosses 23 and the bottom of header 25^a, between each 60 two abutting pipe bosses 23, between pipe

bosses 23 and casting 30 and underneath the nuts on rods 29 so that neither steam nor water can escape at these points. The other side of the boiler is connected in a similar manner with the exception that a casting 31 70 is secured to the lowermost header 14. This casting is similar to casting 30 with the exception that it is provided with an inlet 32 through which water may be supplied to the boiler.

75 Burner 12 is then mounted on the bottom of boiler casing 13 and the casing assembled around the boiler in any suitable manner. The casing preferably consists of a rigid outer shell 33, which encloses a wall of heat resisting material 34, such as asbestos, and is shaped around or secured to the headers. The spaces between the headers and between pipe bosses 23 are preferably packed solid with a heat resisting compound 35, such as asbestos cement, and a metal plate 36 covers the space 80 opposite cover plates 20 and is secured to shell 33 in any suitable manner.

85 Fuel may be supplied to burner 12 through a pipe 37 and the boiler is preferably filled 90 with water, through inlet 32, to the level of the top generating tube. When burner 12 is lighted, the products of combustion must pass upwardly through the different layers and turns of steam generating tubes, pass 95 over the steam tubes and leave the boiler casing through a vent 38. The products of combustion are practically held in boiler casing 13 until all available heat has been absorbed by the steam generating tubes which 100 act as a multitude of baffles to the hot gases; air, for supplying the burner, being admitted to casing 13 in any suitable manner.

105 In operation, I find that a boiler constructed as above described, is capable of producing an enormous amount of steam, relatively to its size. Also, due to the multiplicity of steam generating tubes, it extracts all the available heat from the fuel so that it not only has a large capacity but is also 110 economical.

115 Casing 13 is preferably made in sections, secured together in any suitable manner, so that replacement or repair may be made to one of the steam generating units or the steam unit with a minimum of expense. The steam tubes and generating tubes may be inspected or cleaned by removing plates 36 and cover plates 20 without disturbing any other portion of the boiler.

120 Various changes in the details of the construction of the embodiments hereinbefore set forth may be made within the spirit of the invention herein set forth and hereinafter claimed.

125 I claim:

1. A steam generator including a pair of headers; a plurality of tubes extending from one header, making more than a complete turn spirally to form coils, and entering the 130

other header; a plurality of tubes extending from one header, bending upwardly and forwardly to pass through the coils, and entering the other header; and means for heating the tubes.

2. A steam generator including a pair of headers; a plurality of tubes extending from one header, making more than a complete turn spirally to form coils, and entering the other header, said tubes being disposed in both vertical and horizontal rows in the region adjacent each header; and means for heating the tubes.

3. A steam generator including a pair of headers; a row of generating tubes extending from one header, making more than a complete turn spirally around the axes of the generator, and entering the other header; a second pair of headers in communication with the upper portions of said first pair of headers; a horizontal row of steam tubes extending from one header of the second pair, making more than a complete turn spirally around the axes of the generator and entering the other header of said second pair; and means for heating the tubes.

4. A steam generator including a casing, a steam generating unit in the casing, a steam storage unit connected to the generating unit, and a burner for supplying heat to the units; each unit having a pair of headers and a plurality of horizontal rows of tubes connecting the headers and formed into coils encircling the axis of the generator.

5. A sectional steam generator including a casing, a steam storage unit in the casing, a plurality of steam generating units connected to each other and to the storage unit, and a burner for supplying heat to the units; each unit having a pair of headers and a plurality of rows of tubes connecting the headers and formed into coils encircling the axis of the generator; the generating units having also a plurality of bent tubes connecting the headers and extending through said coils.

6. A sectional steam generator including a casing, a steam storage unit in the casing, a plurality of steam generating units connected to each other and to the storage unit, and a burner for supplying heat to the units; each unit having a pair of headers and a plurality of tubes connecting the headers and formed into coils therebetween; the tubes in each generating unit leaving and entering the headers in horizontal and vertical rows and each of these units also having a plurality of bent tubes connecting the headers and extending through the coils formed by the first mentioned tubes.

7. In a boiler composed of a plurality of units; a steam generating unit including a pair of headers; a plurality of tubes, disposed one above the other to form a set, extending from one header, making more than a complete turn spirally to form coils substantially

equi-distant throughout, and entering the other header; and additional sets of tubes extending from one header in the same vertical planes as the first mentioned set of tubes, making more than a complete turn spirally to form coils concentric with the first mentioned coil and with each other, and entering the other header.

8. In a boiler composed of a plurality of units; a steam generating unit including a pair of headers; a plurality of tubes, disposed one above the other to form a set, extending from one header, making more than a complete turn spirally to form parallel coils, and entering the other header; additional sets of tubes extending from one header in the same plane as the first mentioned set of tubes, making more than a complete turn spirally to form coils concentric with the first mentioned coil and with each other, and entering the other header; and a plurality of tubes extending from one header, bending upwardly and forwardly to pass through the coils and entering the other header.

9. A steam generator including a pair of headers; a tube extending from one header, making substantially one and one-half turns spirally around the axis of the generator to form a coil and entering the other header; other tubes extending from one header in the same horizontal plane as the first mentioned tube, making substantially one and one-half turns spirally to form coils concentric with the first mentioned coil and entering the other header; other tubes extending from one header directly below the first mentioned tubes, making substantially one and one-half turns spirally to form coils in vertical alignment with the upper coils and entering the other header, and means for heating the tubes.

10. A steam generator including a pair of headers; a tube extending from one header, making substantially one and one-half turns spirally around the axis of the generator to form a coil and entering the other header; other tubes extending from one header in the same horizontal plane as the first mentioned tube, making substantially one and one-half turns spirally to form coils concentric with the first mentioned coil and entering the other header; other tubes extending from one header directly below the first mentioned tubes, making substantially one and one-half turns spirally to form coils in vertical alignment with the upper coils and entering the other header; tubes extending from one header, bending upwardly, passing through the innermost coils and entering the other header, and means for heating the tubes.

In testimony whereof I have signed my name to this specification.

EARL V. VARCOE.
